H. DIEDERICH.

ELECTRIC LAMP AND FAN.

APPLICATION FILED JUNE 16, 1919.

1,345,752.

Patented July 6, 1920.

FIG. 1.

2
inventori

1755.00
Hunt Diederich,
by his attorney.

my dear son,
Charles V. Gooding.

UNITED STATES PATENT OFFICE.

HUNT DIEDERICH, OF NEW YORK, N. Y.

ELECTRIC LAMP AND FAN.

1,345,752.

Specification of Letters Patent. Patented July 6, 1920.

Application filed June 16, 1919. Serial No. 304,501.

To all whom it may concern:

Be it known that I, HUNT DIEDERICH, a citizen of the United States, residing at New York city, in the county of New York and State of New York, have invented new and useful Improvements in Electric Lamps and Fans, of which the following is a specification.

This invention relates to an ornamental and useful device embodying an electric lamp and a rotary fan, the object of the device being to provide an ornamental device which may be used as an electric lamp or as an electric fan, or may be used simultaneously as a fan and lamp.

The device has a casing of a form similar to the Dutch windmills and upon the outside the fan which completes the appearance of a windmill, while at the same time being capable of cooling the air in the usual manner of an electric fan. A portion of the casing is provided with openings and the electric lamp is positioned within the casing so as to cast rays of light through the openings and across the fan. The appearance of the device, with the rays of light shining on the blades of the fan, is very artistic and attractive, while at the same time it provides a very compact and convenient means for lighting and cooling a room.

A guard is also provided around the fan, said guard constituting in effect a switch, it being necessary that said guard shall always be in place around the fan before the motor can be started and fan operated. The guard when lowered represents a rustic fence extending around the base of the windmill.

The invention consists in the combination and arrangement of parts set forth in the following specification and particularly pointed out in the claims thereof.

Referring to the drawings: Figure 1 is a sectional elevation of my improved lamp and fan. Fig. 2 is a diagrammatic view of the electric circuits.

In the drawing, 1 is a casing consisting of a base 2, a hollow frusto-conical portion 3, a cylindrical portion 4 provided with openings 4', representing windows, and a conical portion 5, representing the roof of

the windmill. A cylindrical sleeve 6 encircles the cylindrical portion 4 of the casing and is slideable vertically thereon. When 55 in its lowered position it rests as shown in dotted lines upon an annular support 7 which is fastened to the frusto-conical portion 3.

The fan 8 is fastened to a shaft 9 which 60 is rotatably mounted in bearings 10 and 11 upon the cylindrical portion of the casing and has fastened to its inner end a pulley 12. The pulley 12 is rotated by means of a belt 13 which is driven by a pulley 14 on 65 the shaft 15 of an electric motor 16.

An electric lamp 17 is held in a socket 18 which is supported upon a brace 19 fastened to the upper end of the frusto-conical portion 3.

70

A guard 20 is provided to prevent accidents resulting from coming in contact with the fan, said guard consisting of annular members 21 and 22 between which extend at regular intervals rods 23. The guard 20 is 75 supported and pivoted at 24 upon a bracket 25 fast to the front of the windmill, and is further supported from above by means of a brace 26 which has attached thereto a plug 27 adapted to fit a socket 28 constructed of insulating material and located at the apex of the roof 5 of the windmill. The plug 27 and socket 28 constitute a switch 80 and it is necessary that the electric circuit hereinafter to be described shall always be 85 completed through this switch before the fan can be operated.

When it is not intended to operate the fan, the guard 20 may be lowered by removing the plug 27 from the socket 28 and allowing 90 said guard to drop to the position illustrated in dotted lines at which time said guard represents a rustic fence extending around said windmill.

The device is operated and controlled by 95 electric circuits as follows: Upon the interior of the windmill is located a switch 29, the said switch being fastened to the inside of the frusto-conical portion 3 of the casing. The switch 29 includes an insulating plate 100 30 provided with terminals 31 and 32 to which are connected wires 33 and 34, which, in turn, are connected to a suitable source of electric power 35. The switch 29 further

includes contact plates 36 and 37 and a contact arm 38. A wire 39 connects the terminal 31 with the terminal 40 on the motor 16, while a wire 41 connects a second terminal 42 on the motor, with a terminal 43 provided in the socket 28. A second terminal 44 in the socket 28 is connected by a wire 45 with the contact plate 36, and the contact arm 38 is connected with the terminal 32 by a wire 46. The electric lamp 17 is connected by wires 47 and 48 to the terminal 31 and contact plate 37 respectively.

A door 49 is hinged at 50 to the frusto-conical portion of the casing and is held closed by means of a latch 51. Said door is made of rustic design and appearance and provides a means of access to the electric switch 29 whereby the electric circuits may be controlled.

20 The general operation of the device is as follows: If it is desired to use the device simply as a fan without the light, then the sleeve 6 is pushed upwardly to the position shown in the drawings and the openings 4' 25 are thus closed. The guard 20 is next raised into position to surround the fan 8 and the plug 27 is inserted in the socket 28, thereby connecting the terminals 43 and 44. The electric motor 16 is then set in operation by 30 opening the door 49 and moving the contact arm 38 of the switch 29 into engagement with the contact plate 36. This completes the independent fan operating circuit. The fan may be stopped at any time if desired 35 by simply removing the plug 27 from the socket 28.

If it is desired to use the device as a lamp and fan combined, the contact arm 38 is moved so that it will not only engage the 40 contact plate 36, but it will also engage the contact plate 37. In this manner the fan operating circuit is completed. At this time the cylindrical sleeve 6 is in its lowered position resting upon the annular support 7. If 45 it is desired to stop the fan during the times when the fan is in operation and also when the lamp is lighted, it is only necessary to remove the plug 27 from contact with the terminals 43 and 44, thereby breaking the fan 50 circuit but leaving the lamp circuit completed.

If it is desired to use the electric lamp alone, and have the fan remain stationary, the guard 20 is preferably lowered to the 55 position illustrated in dotted lines. This will cause the fan circuit to be broken between the terminals 43 and 44 and make it impossible for the fan to again be operated until the guard 20 is again placed in position. It is preferable at this time to have the contact arm 38 in engagement with the contact plate 37 only, although it is not necessary. In each case the lamp circuit 60 only is completed.

65 It will thus be seen that my device is not

only ornamental, but very useful and is capable of being used separately either as a lamp or fan, or as a combined lamp and fan.

Having thus described my invention, what I claim and desire by Letters Patent to secure is:

1. A device of the character described having, in combination, a hollow casing provided with openings, an electric motor within said casing, a fan rotatably mounted on the outside of said casing in alinement with said openings, means connecting said motor to said fan, whereby a rotary motion may be imparted thereto, and an electric lamp located within said casing and positioned to cast rays of light through said openings and across said fan.

2. A device of the character described having, in combination, a hollow casing provided with openings, an electric motor within said casing, a fan rotatably mounted on the outside of said casing in alinement with said openings, a member constructed and arranged to either constitute a guard for said fan or a fence around said hollow casing, means connecting said motor to said fan whereby a rotary motion may be imparted thereto, and an electric lamp located within said casing and positioned to cast rays of light through said openings and across said fan.

3. A device of the character described having, in combination, a hollow casing provided with openings, an electric motor within said casing, a fan rotatably mounted on the outside of said casing in alinement with said openings, means connecting said motor to said fan whereby a rotary motion may be imparted thereto, and an electric lamp located within said casing and positioned to cast rays of light through said openings and across said fan, said electric lamp being in a separate electric circuit from the circuit which includes the motor.

4. A device of the character described having, in combination, a base, a frusto-conical body portion fast to said base, a cylindrical body portion located above said frusto-conical portion, a conical top located above said cylindrical portion, a fan rotatably mounted upon said cylindrical portion, said cylindrical portion being provided with openings therein in alinement with said fan, an electric motor located upon said base, means connecting said motor to said fan whereby a rotary motion may be imparted thereto, and an electric lamp located within said cylindrical portion and positioned to cast rays of light through said openings and across said fan.

5. A device of the character described having, in combination, a base, a frusto-conical portion fast to said base and projecting upwardly therefrom, a cylindrical portion located above said frusto-conical

portion, said cylindrical portion being provided with openings, a cylindrical sleeve slidably mounted upon said cylindrical portion, a fan rotatably mounted on said cylindrical portion in alignment with said openings, an electric motor located upon said base, means connecting said motor to said fan whereby a rotary motion may be imparted thereto, and an electric lamp lo-

cated within said cylindrical portion positioned to cast rays of light through said openings and across said fan, said electric lamp being in a separate electric circuit from the circuit which includes the motor. 10

In testimony whereof, I have hereunto set 15
my hand.

HUNT DIEDERICH.
